UNITED STATES PATENT OFFICE.

NATHAN BARNEY, OF BROOKLYN, NEW YORK.

DUMPING-CAR.

SPECIFICATION forming part of Letters Patent No. 544,020, dated August 6, 1895.

Application filed April 1, 1895. Serial No. 543,968. (No model.)

To all whom it may concern:

Be it known that I, NATHAN BARNEY, of Brooklyn, in the county of Kings and State of New York, have invented a new and useful Improvement in Dumping-Cars, of which the following is a specification.

My invention relates to an improvement in dumping-cars, and relates more particularly to means for raising and lowering the trap-
doors of said cars.

The object of my invention is to provide a very simple and effective mechanism for raising and lowering the trap-doors, which mechanism is mounted within the car-body.

15 A practical embodiment of my invention is represented in the accompanying drawings, in which—

Figure 1 is a longitudinal vertical central section through a portion of a dumping-car, 20 the trap-doors being shown closed in full lines and open in dotted lines. Fig. 2 is a transverse vertical central section through the car. Fig. 3 is a transverse vertical section through a car, showing a modified form of operating mechanism; and Fig. 4 is an enlarged view 25 of the ratchet mechanism for holding the trap-doors closed.

The class of car to which my invention is applied is that commonly known as the "gondola" type, in which the bottom of the car slopes downwardly toward the center to form 30 a suitable hopper, the mouth of the hopper being closed by suitable trap-doors hinged so as to swing toward and away from each other 35 to open and close communication through the bottom of the car.

The longitudinal side timbers of the framework of the car are denoted by A A', and the two center timbers are denoted by A² A³.

40 The hopper of the car is denoted by B, and it is provided with suitable swinging trap-doors b b', which are hinged to the bottom of the hopper on their opposite edges, their inner edges being adapted to swing up into 45 close contact with each other.

The main shaft is designated by C and is mounted in suitable bearings c c' on the side timbers A A'. The ends of the shaft C project through the side of the car-body and are 50 squared for the reception of a suitable crank-handle c² thereon for rotating the said shaft.

The shaft C is further provided, at one or

both ends, with a ratchet-wheel c³, which is adapted to be engaged by a suitable pawl c⁴, which pawl is adapted to lock the shaft C 55 against rotation in either direction when it engages the ratchet-wheel c³. The shaft C is further provided with a pinion c⁵, which is located between the two center timbers A² A³.

The crank-shaft D is mounted in suitable 60 bearings d, which bearings are secured to the center timbers A² A³. The crank-arms of the crank-shaft D are denoted by d' d². In the present instance the crank-arm d' is a gear-wheel which meshes with the pinion c⁵ upon 65 the shaft C, so that as the shaft C is rotated the crank-shaft D will also be turned. The wrist-pin of the crank-shaft D is denoted by d³ and extends from the gear-wheel d' to the other arm d² of the crank-shaft. On this wrist- 70 pin d³ I mount the upper ends of branch rods E E', the lower ends of the said rods being connected the one to the trap-door b and the other to the trap-door b', so that as the crank-shaft D is turned the doors b b' will be opened 75 or closed.

In the modified form shown in Fig. 3 the shaft C is provided with a second pinion c⁶, which intermeshes with the crank-arm d², which in this instance is a gear-wheel corresponding to the gear-wheel d', which meshes 80 with the pinion c⁵ on the said shaft C. It may be desirable to use this form for greater strength or positiveness in action.

A suitable box or casing F is secured to 85 the center timbers A² A³ and protects the operating parts of the device. The bottom of this casing F is provided with a suitable opening f, through which the branch rods E E' project. 90

In operation, supposing the trap-doors to be closed and it be desired to dump the load of earth, coal, or other material, the pawl c⁴ is released from its engagement with the ratchet-wheel c³ and the crank-handle c² is 95 turned, thereby causing the crank-shaft D, by means of its gear connection with the shaft C, to turn, which will cause the doors b b' to swing apart, allowing the material to pass therethrough. After the load has been 100 dumped the crank-handle may be turned until the wrist-pin d³ assumes its highest point, when the doors b b' will be closed. The pawl c⁴ is then caused to engage the

ratchet-wheel c^3 , which engagement will lock the doors in their closed position.

By locating the door-operating mechanism in the center of the car I am enabled to use 5 only one set of operating devices for each car instead of two sets, where the said mechanism is located upon the opposite sides of the car-body. This is a very important feature, as it allows of the doors being closed more 10 positively and effectively.

It is obvious that slight changes might be resorted to in the form and arrangement of the several parts without departing from the spirit and scope of my invention. Hence I 15 do not wish to limit myself strictly to the structure herein set forth; but

What I claim is—

1. The combination with a car having a pair of swinging doors in its bottom, of a 20 main shaft extending through the car body, a pinion carried by said shaft, a crank shaft, a gear wheel on the crank shaft intermeshing

with the said pinion, and branch rods connecting the crank shaft with the doors, whereby the turning of the main shaft operates the 25 doors, substantially as set forth.

2. The combination with a car having a pair of swinging doors in its bottom, of a car frame comprising side and center longitudinally extending timbers, a main shaft extending transversely across the car body and mounted in bearings on the said timbers, a pinion on said shaft, a crank shaft mounted in bearings on the center timbers, a gear wheel thereon intermeshing with the pinion 30 on the main shaft, and branch rods connecting the crank shaft with the swinging doors, whereby as the main shaft is rotated the doors are opened or closed, substantially as set forth.

NATHAN BARNEY.
